UNITED STATES PATENT OFFICE.

PETER LINDEN, OF TROY, NEW YORK, ASSIGNOR OF ONE-HALF TO DENNIS PETERS, OF SAME PLACE.

HEEL FOR BOOTS OR SHOES.

SPECIFICATION forming part of Letters Patent No. 372,688, dated November 8, 1887.

Application filed February 25, 1887. Serial No. 228,836. (No model.)

To all whom it may concern.

Be it known that I, PETER LINDEN, a resident of the city of Troy, in the county of Rensselaer and State of New York, have invented 5 certain new and useful Improvements in Heels for Boots or Shoes; and I do hereby declare that the following is a full, clear, and exact description of the invention, that will enable others skilled in the art to which it appertains to 10 make and use the same, reference being had to the accompanying drawings, and to the letters of reference marked thereon, which form a part of this specification.

Similar letters refer to similar parts in the 15 several figures therein.

My invention relates to improvements in boot-heels; and it consists of the novel construction and combination of parts, hereinafter described, and pointed out in the claim.

20 The object of the invention is set forth in connection with the following description.

Figure 1 of the drawings is a side elevation of a boot or shoe provided with my improved heel. Fig. 2 is a vertical cross-section, taken 25 on the broken line XX in Fig. 3, on an enlarged scale. Fig. 3 is a bottom plan view of the heel on a scale still further enlarged.

The improved heel H may be applied to any 30 of the well-known forms of boots or shoes, as shoe S. The "upper" B is folded in upon the insole C, and one edge of the welt D laid upon the upper in alignment therewith around the heel, as shown by dotted lines in Fig. 3. The three parts may then be secured together by 35 pegs or stitches a, extending around the heel. When desired, the edge of the upper may be first secured to the edge of the insole and the welt afterward secured to the parts so united, the other or loose edge of the welt occuring about the position shown by dotted lines in Fig. 2. An elastic cushion, A, preferably of rubber, is then laid upon the welt and the loose edges of the latter folded over upon

the cushion, and the first of the lifts E, forming the lower part of the heel, laid thereon and secured to the folded edge of the welt by the pegs or stitches b, extending around the heel. 45

Other lifts, in any desired number, may be added and secured upon the heel to form a part thereof, by the pegs d.

The completed shoe has interposed within 50 the heel an elastic cushion, which is securely held therein without being stitched or pegged to any part of the boot or shoe.

The elastic material is perfectly free to yield 55 and recover while in use.

I am thus able to provide boots and shoes with an elastic heel which affords great ease and comfort to the wearer while walking, especially upon the hard pavements of cities, and 60 does not deface the appearance and form of the shoe.

No particular form is essential to the elastic material, though I prefer to make it of elastic sheets similar in outline to the general form of 65 the heel, substantially as shown in plan view in Fig. 3.

What I claim as new, and desire to secure by Letters Patent, is—

The herein-described boot-heel, which consists of an elastic cushion inclosed within and supported by a welt folded upon the edge of the cushion, substantially as described, one edge of the welt being secured to the contiguous edge of the upper part of the boot or shoe, 75 and the opposite edge of the welt to one or more heel-lifts, which are supported thereby, all the parts being arranged substantially as described, and for the purposes set forth.

In testimony whereof I have hereunto set 80 my hand this 21st day of February, 1887.

PETER LINDEN.
